US00D883992S

(12) **United States Design Patent** (10) Patent No.: **US D883,992 S**
Chen (45) Date of Patent: **** May 12, 2020**

(54) **DISPLAY SCREEN WITH GRAPHICAL USER INTERFACE**

(71) Applicant: **Tencent Technology (Shenzhen) Company Limited**, Shenzhen, Guangdong (CN)

(72) Inventor: **Wen Jun Chen**, Shenzhen (CN)

(73) Assignee: **Tencent Technology (Shenzhen) Company Limited (CN)**

(**) Term: **15 Years**

(21) Appl. No.: **29/626,784**

(22) Filed: **Nov. 20, 2017**

(30) **Foreign Application Priority Data**

Jun. 7, 2017 (CN) 2017 3 0228769

(51) **LOC (12) Cl.** **14-04**

CLAIM

The ornamental design for a display screen with graphical user interface, as shown and described.

DESCRIPTION

FIG. 1 is a front view of a first embodiment of a display screen with graphical user interface showing my new design;

FIG. 2 is a front view of a second embodiment of a display screen with graphical user interface showing my new design;

FIG. 3 is a front view of a third embodiment of a display screen with graphical user interface showing my new design; and,

FIG. 4 is a front view of a fourth embodiment of a display screen with graphical user interface showing my new design.

The broken line showing of portions of the display screen and a mobile device in FIGS. 1 through 4 represents environmental structure forms no part of the claimed design. The broken line showing of text and portions of the graphical user interface in FIGS. 1 through 4 forms no part of the claimed design.

1 Claim, 4 Drawing Sheets
